UNITED STATES PATENT OFFICE.

WILLIAM G. KENDALL, OF NEWARK, NEW JERSEY, ASSIGNOR, BY MESNE ASSIGNMENTS, TO PARFUMERIE RIGAUD, INC., OF NEW YORK, N. Y., A CORPORATION OF NEW YORK.

CONTAINER FOR TOILET POWDERS.

Application filed November 18, 1924. Serial No. 750,529.

This invention relates to improvements in containers for toilet powders and more particularly to that type of container which is designed to deliver a small quantity of loose face powder at one time.

Another object of the invention is to provide a metal container for loose face powder which will have all the beauty and convenience of the metal compact holders, but which will be at the same time so made as to deliver a small quantity of loose face powder without the effort required to remove a small quantity of powder from a compact.

Another object of this invention is to provide a holder of the type described which will automatically prevent the spilling of loose face powder and which can be operated with a minimum of effort.

Further objects of the invention will be apparent from the specification and drawings in which—

Fig. 1 is a top view of my improved holder with the cover open.

Fig. 2 is a vertical cross section along the line 2—2 of Fig. 1.

Fig. 3 is a plan view of the bottom of the powder delivery device, the top of which is seen in Fig. 1.

Fig. 4 is an enlarged view of the spring member and holder for the spring employed in this device.

1 is a box of the ordinary type for holding powder and 2 is the cover therefor.

The box 1 has an interior lining 3 having a bevelled surface 4 to which the plate 5 is fitted, so that the cooperating surfaces of the plate 5 and the bevelled edge 4 will fit tightly against each other so as to prevent the egress of any powder which is contained in the box. In the plate 5 are punched a series of small holes 6, 6, 6, through which the powder filters when said holes are open. Another plate 8 having a diameter large enough to cover all of the holes 6, is located under the plate 5. Small hemispherical knobs 9 which are adapted to tightly fit into the holes 6 are struck out of closure plate 5, so that these closure knobs 9 remain integral with plate 5. A larger convex member 10 is similarly formed at the center of plate 8 and this protrudes through the central hole 7 of plate 5 and acts as a fingerhold by means of which the plate 5 is actuated. A spring member is in engagement

with the plate 8 so as to push the plate 8 upward and cause the members 9 to effectively close the holes 6. This concave spring member 11 may be fastened to the plate 8 to cause it to engage slots in said plate or said member 11 may be fastened to the bottom of the plate 8 in any suitable manner.

It will be seen that when the fingerhold 10 is depressed so that the protuberances 9 will be moved below the position in which they effectively close holes 6 that a small portion of powder can be expelled from the box through said holes 6. The action of spring 11 causes plate 8 to automatically come back into position so as to close the holes 6 so that no powder can sift from the device when the spring 11 forces plate 8 to what may be termed its normal closure position.

It will be apparent that variations may be made in the construction of the plates 5 and 8 and also of the spring 11 without departing from the spirit of this invention.

For instance, the fingerhold 10 need not be made integral with the plate 8, but may be made as a separate member and thereafter fastened to the plate 8. It will also be apparent that other forms of springs may be used than the specific form herein illustrated.

I have here provided an efficient and convenient device for securing a small quantity of loose face powder from a container wherein the loose face powder will not be spilt when not wanted.

Having fully described my invention, what I claim is:

1. A toilet powder container having a plate fitting against the wall of the said container, the said plate having a substantially central opening and a plurality of orifices laterally disposed with respect to the said central opening, a second plate free from said first plate, the second plate having a projection adapted to project through the said central opening and by means of which the said second plate can be manipulated, the second plate also having projections adapted to enter the said orifices and to substantially close the same, and spring means connected to the second plate and adapted to normally hold it in the closing position, the said second plate being free to move with respect to the said first plate along a straight line sub-

stantially perpendicular to the first plate, the second plate being located intermediate said spring means and the first plate.

2. A device according to claim 1 in which said spring means comprises a concave springy plate having an edge abutting the bottom of the said container.

3. In a toilet powder container, a holder for the powder, a plate fitting said holder and acting as a cover for said powder, a series of orifices around the center of said plate, a supplementary plate having a series of protuberances fitting said orifices and positioned under said plate, a spring connected to the center of said supplementary plate and normally holding said protuberances in engagement with said orifices, and a finger-hold attached to the under plate and passing through the upper plate, permitting the

opening of said orifices simultaneously so that said orifices are opened by the downward pressure on said spring.

4. In a toilet powder container, a box acting as the container of said powder, a plate tightly fitting said box and acting as the cover of said container, a series of orifices on said plate, another plate under said top plate having a series of cone-shaped protuberances integrally formed thereon fitting said orifices, a spring fastened to said lower plate holding said protuberances normally in engagement with said orifices, and a finger-hold fastened to said spring so that by pressure on said spring powder can be simultaneously released from all of said orifices.

In testimony whereof I hereunto affix my signature.

WILLIAM G. KENDALL.
